UNITED STATES PATENT OFFICE

JULES SCHWAB, OF NEW YORK, N. Y.

DESIGN FOR A NECKLACE

Application filed April 3, 1931. Serial No. 39,359. Term of patent 3½ years.

To all whom it may concern:

Be it known that I, JULES SCHWAB, a citizen of the United States, residing at New York, in the county of New York, and State of New York, have invented a new, original, and ornamental Design for a Necklace, of which the following is a specification, reference being had to the accompanying drawing, forming a part thereof.

The figure is a perspective view of my new design for a necklace.

I claim:

The ornamental design for a necklace, as shown.

JULES SCHWAB.
